(57) **CLAIM**

The ornamental design for a belt organizer, as shown and described.

DESCRIPTION

FIG. 1 is a perspective view of a belt organizer showing my new design;

FIG. 2 is another perspective view thereof;

FIG. 3 is a front elevational view thereof, with the rear elevational view, the left side view, and the right side view being identical;

FIG. 4 is a top plan view thereof, with the bottom plan view being identical;

FIG. 5 is a perspective view of the belt organizer shown in an alternate configuration in an open state;

FIG. 6 is another perspective view thereof;

FIG. 7 is a front elevational view thereof, with the rear elevational view, the left side view, and the right side view being identical; and,

FIG. 8 is a perspective view of the belt organizer of FIG. 1, shown in an environment of use.

The broken lines in the figures are for the purposes of illustrating environmental structure and form no part of the claimed design.

1 Claim, 7 Drawing Sheets
